UNITED STATES PATENT OFFICE

CLAUDE A. STRAIT, OF DULUTH, MINNESOTA

RAIL ANCHOR

Application filed August 6, 1928. Serial No. 297,628.

The present invention relates to a rail anchor for anchoring rails against creeping. In case where most of the traffic on a railroad is in one direction or where the heavy traffic is in one direction with the empty cars returning in the opposite direction the rails have a tendency to creep along the ties. Various devices have been employed to correct or arrest this creeping of the rails but most of these devices are either so complicated as to be expensive and difficult to install or else have a tendency to loosen and thus destroy their usefulness.

An object of the present invention is to make a strong, simple, and effective rail anchor which may easily be installed and which will require a minimum of up-keep and repairs.

In order to attain this object there is provided, in accordance with one feature of the invention, a pair of jaw members adapted to engage the sides of the base portion of a rail, one of said members being adapted to lockingly engage the head of said bolt. These members are positioned to engage a side of a railroad tie to anchor the rail against creeping. These and other features of the invention will be more fully brought out in the following description and the accompanying drawings wherein:

Figure 1, is a view in top plan of a portion of a rail mounted upon a portion of a tie with the anchor device in position on the base of the rail.

Figure 2, is a vertical sectional view of the device shown in Figure 1 showing the rail in section and the tie and anchoring member in elevation.

Figure 3, is a vertical sectional view through the anchoring member and the base of the rail.

Figure 4, is a view in perspective, of one of the jaw members that engage the base of the rail.

Figure 5, is a view also in perspective, of the other jaw member.

Figure 6, is a sectional view on the line 6-6 of Figure 3.

Referring to the drawings in detail, the anchor comprises a jaw member 1 having a

recess 2 therein to engage the base flange 3 of a railway rail 4. This jaw member is provided with opening 5 threaded to receive a bolt 6. The other jaw member 7 is constructed with a recess 8 to receive the other edge of the base flange of the rail 4 and is provided with an opening 9 in which the bolt 6 is freely insertable. A groove 10 is provided vertically of the jaw member 7 to receive a lock-pin 11 to prevent rotation of the bolt 6 with respect to the jaw member 7. The inner face of the head of the bolt 6 is provided with four grooves 12 one adjacent to each edge of the head of the bolt 6 to register with the locking-pin groove 10 of the anchor member 7 for each 90 degrees rotation of the bolt 6.

In using the device a jaw member 7 is slipped over the shank of the bolt 6 and the bolt is threaded into the opening 5 in the jaw member 1. The jaws are separated to a distance greater than the width of the base-flange of the rail and are then slipped beneath the base-flange of the rail and the device is moved closely adjacent a side of the tie toward the direction from which the heaviest traffic comes. The bolt 6 is then turned by a means of a suitable wrench to draw the jaws 1 and 7 together, firmly gripping the base-flange of the rail 4 between them.

When drawn to the point of maximum pressure the bolt head is turned so that one of the grooves 12 in the bolt-head is in register with the locking-pin groove 10 in the jaw member 7. A locking-pin which is preferably of a size to have a close driving fit in the opening provided by the grooves 10 and 12 is then driven into this opening to firmly lock the bolt 6 against rotation relative to the jaw member 7 and the rail base. The other jaw member 1 is of course held against rotation by its engagement with the base-flange of the rail so that no displacement of any of the parts is possible without distorting some of the members or removing the locking-pin 11.

The device is simple and effective in operation, easy to install and as it comprises but four operative parts including the locking-pin the cost of the device is extremely low. The device may be shipped completely assem-

bled except for the locking-pin so that there are no loose nuts or parts to be lost.

I claim:

A rail anchor, comprising a bolt having a groove on the inner face of the head thereof, a jaw member having a rail gripping groove at the top on the inner side thereof and having a portion thereof extending below the bolt when in an operative position to engage 10 a tie, and having a smaller groove in the outer face thereof to coincide with the groove in the bolt head; a second jaw member having a groove therein to lie above the bolt on the inner side of said jaw member when said jaw 15 member is in an operative position and having an extension beneath the bolt when the jaw member is in an operative position to engage a tie, and having a threaded opening therein to threadedly receive the bolt to draw 20 the jaw members together to grip a rail flange therebetween, and a pin adapted to be inserted in the opening formed by the coinciding grooves on the inner side of the head in the outer side of the first jaw members to 25 prevent rotation of the bolt with respect to the jaw members.

In testimony whereof I affix my signature.

CLAUDE A. STRAIT.
